UNITED STATES PATENT OFFICE.

JOHN W. PATTERSON, OF TISKILWA, ILLINOIS.

WAGON-BRACKET.

No. 818,283.

Specification of Letters Patent.

Patented April 17, 1906.

Application filed March 15, 1905. Serial No. 250,257.

To all whom it may concern:

Be it known that I, JOHN W. PATTERSON, a citizen of the United States, residing at Tiskilwa, in the county of Bureau and State of Illinois, have invented new and useful Improvements in Wagon-Brackets, of which the following is a specification.

The invention relates to an improvement in wagon-brackets designed particularly for use in converting the ordinary farm-wagon into a hay-wagon.

The main object of the invention is the production of a bracket designed for removable connection with the wagon-bolster and with the longitudinal sills of the wagon-body and arranged to secure and support the transverse frame-bars of the hay-rack.

The preferred form of the invention will be described in detail in the following specification, with reference to the accompanying drawings, in which—

Figure 1 is a view in elevation, showing a wagon-body arranged for use as a hay-wagon with my improved bracket in place. Fig. 2 is an enlarged view in elevation with the wagon-sills in section, illustrating the application of my improved bracket. Fig. 3 is a perspective view of the bracket.

In adapting the ordinary farm-wagon for use as a hay-wagon it is necessary to remove the wagon-body and support the hay-rack from the longitudinal sills of the wagon-frame. To provide for the convenient attachment of the hay-rack, I have devised a bracket designed to be removably secured to the wagon-sills and to the transverse bars of the hay-rack, whereby the latter may be readily and securely attached to and supported from said longitudinal sills.

The bracket of my invention comprises, preferably, an integral casting having a body portion 1, a rack-plate 2, projecting at a right angle from the upper end of the body portion, and a bolster-plate 3, projecting at a right angle from the lower end of the body portion, but in a reverse direction from that of the hay-rack plate 2. Depending from the under side of the rack-plate 2 is an angle-plate 3', the downwardly-projecting flange 4 of which extends in alinement with the body portion 1, but spaced therefrom a sufficient distance to receive the edge of one of the longitudinal wagon-sills. The free end of the rack-plate 2 is enlarged, as at 5, and provided

with a U-shaped retaining-bolt 6, the terminals of which are arranged to pass through suitable openings in the enlarged end 5 of the plate 2 and be secured beneath said plate by nuts 7. The distance between the vertical members of the retaining-bolt 6 is such as to receive the transverse frame-bar of the hay-rack.

In securing the bracket in place the body portion 1 is placed in contact with the inner side of the longitudinal wagon-sill 8, being secured thereto by suitable bolt-fastenings 9, the bolster-plate 3 of the bracket resting upon the wagon-bolster 10 and being secured thereto by suitable bolt-fastenings 11. The plate 2 of the bracket projects laterally from the sill 8 in a direction away from the longitudinal center of the wagon, the body portion 1 being of less length than the height of the sill, so that that portion of the plate 2 between the body portion 1 and the vertical flange 4 of the angle-plate 3' seats within a suitable transverse recess 12, formed in the upper edge of the sill. The flange 4 of the angle-plate 3' rests snugly against the longitudinal sill on the side opposite the body portion 1, so that the upper end of the sill is held between the body portion 1 and the flange 4, whereby any accidental movement of the bracket is prevented. The transverse bars 13 of the hay-rack 14 are passed lengthwise through the retaining-bolt 6, the nut 7 of the latter being tightened to draw the cross-bar 15 of the bolt 6 into holding contact with the upper surface of the frame-bar 13.

It is to be understood that as many brackets as desired may be used, and that said brackets are firmly secured to the wagon-bolster and body-sills, and that the hay-rack bars are removably secured to the brackets by the retaining-bolts 6. The retaining-bolts are preferably disconnected from the plates 2 and the hay-rack put in place with the transverse bars 13 alined above the plates 2, when the terminals of the retaining or loop bolts 6 may be passed through the plates and secured by the nuts 7.

It will be noted that my construction provides for supporting the hay-rack directly from the sills of the wagon-body, the brackets being used as a connecting medium between the wagon-body and hay-rack.

While I prefer that the angle-plate 3 be riveted or otherwise secured in proper posi-

tion on the plate 2, the same may, however, be formed in one piece with the bracket, if desired.

Having thus described the invention, what is claimed as new is—

A wagon-bracket comprising an integral plate bent at one end to provide a bolster-plate, projected vertically at right angles from said bolster-plate to provide a body portion, and bent at right angles from the upper end of the body portion in a direction reverse to the direction of the bolster-plate to provide a rack-plate, the outer end of the rack-plate being laterally extended, a loop-retain-

ing bolt secured in said extended portions of 15 the rack-plate, and an angle-plate secured to the under side of the rack-plate with a depending portion parallel to but spaced from the body portion of the bracket, said body portion being provided with means for securing same to a wagon-sill. 20

In testimony whereof I affix my signature in presence of two witnesses.

JOHN W. PATTERSON.
